POWER AMPLIFIER AND TRANSMITTER
AND THE LIKE

James L. Hogan, New York, N. Y.

Application January 5, 1939, Serial No. 249,434

4 Claims. (Cl. 250—27)

The purpose of this invention is to provide improvements in series A. C./D. C. power circuits for all wave band radio receivers, power amplifiers, transmitters, combination and oscillator circuits, and the like, in which noise is reduced, and in which the different parts may be combined in a common unit.

The invention is a system of radio receiving, power amplifying, and transmitting without static or other noise, with all of the circuits combined in a common unit adapted to be operated by A. C. or D. C. current, and in which are provided, switching devices to cut out the radio frequency and detector units, and cut in a power amplifier as a unit, and also to cut out the speaker and cut in an oscillating tube and circuit for transmitting, and in the system is also a multi-unit line rectifying tube, and a plurality of multi-electrode heater type tubes in series with each other and the rectifying tube.

Many attempts have been made to improve receiving, amplifying, and transmitting apparatus. Such apparatus has been provided in different types and designs, but a single compact unit has not been produced which successfully combines receiving, power amplifying, and transmitting apparatus that eliminates static and noise, and although devices in some patents and in use have resistance coils that may be used for series A. C./D. C. power circuits, these have not, up to the present time, been used in apparatus except for receiving, and in order to make the parts operate successfully in combination it has been found necessary to provide amplifier and power output tubes with their own filters and resistors in their cathode circuits.

In this combination it is also necessary to provide every possible precaution against noise, static, and hum, and therefore the cathodes of the tubes are connected to the chassis through resistors and condensers and the power supply wire.

One object of the invention is to provide a power circuit which can be employed for transmitting, which will have a low current consumption, which will operate without producing internal static, and which will generate pleasing sound wave creating impulses.

Another object of the invention is to provide an improved power circuit which can be constructed with a minimum number of parts and elements, and which can be utilized for transmitting and the like, and which will also operate without generating static disturbances.

Another object is to provide an improved series

A. C.—D. C. power circuit by which it is possible to impress a high voltage upon the plates in the tubes of a vacuum tube circuit in which it is connected to boost amplification and rectification.

Another object of the invention is to provide a power circuit with cathode elements so arranged that the heating effect is produced more efficiently and with less time lag, and may be obtained in its fullest extent.

Another object of the invention is the provision of a power circuit with an improved system of cathode elements and condensers, so arranged that regeneration may be eliminated, and long distance reception or transmitting obtained without fading and without static, and the volume obtained greatly increases, without reducing the tonal quality of the tone and, in fact, improving that quality.

Another object of the invention is to provide an improved power amplifier circuit for vacuum tube circuits which is so designed that it will supply current of the proper kind to the units of a radio receiving or transmitting circuit regardless of whether it is connected with a direct or an alternating current source of supply.

Still another object of the invention is to provide in a power layout employing a coupled transformer and rectifier, in which the possibility of burning out the windings of the transformer will be avoided.

And a still further object is to provide a combination receiving, amplifying and transmitting circuit and the like which is of a simple and economical construction.

With these ends in view the invention embodies a receiving, amplifying, and transmitting unit comprising line rectifying, radio frequency amplifying, detecting, audio amplifying, push-pull amplifying, and oscillating tubes in which the elements thereof are connected in suitable circuits with the cathodes of the tubes individually connected to the chassis through resistors and condensers, and in which parts of said unit may be used for receiving, other parts for power amplifying, and other parts for transmitting.

Other features and advantages of the invention will appear from the following description, taken in connection with the drawings, wherein:

Figure 1 is a diagrammatic view showing the group arrangements of the cathode, heating, and other elements in connection with certain condensers and variable connections in combination

receiving, power amplifying, transmitting, and oscillating circuits.

Fig. 2 illustrates push-pull oscillation and boost high voltage amplification and rectification.

Figure 3 shows another series A. C./D. C. high voltage amplification and full wave rectification power circuit and shows a resistor and condenser in each cathode circuit, for transmitting and the like.

In the drawings typical circuits are illustrated wherein the parts of a receiving unit are shown within the bracket 1, extending from point 1 to point 2, the parts of a power amplifier circuit within the bracket 2, extending from the point 2 to the point 3, and those of the transmitting circuit within the bracket 3, extending from the points 1 or 3 to the point 4.

The device is connected in an A. C. or D. C. circuit by a plug 4 which has wires 5 and 6 leading therefrom with the wire 5 connected to a line switch 7, the opposite terminal of which is connected to wires 8 and 9, and the wire 9 is connected to the chassis through a filtering condenser 10. This switch 7 is used to cut in the power house current. The wire 8 extends to plate 11 and is connected by a wire 12 to a plate 13, both of which plates are positioned in a rectifier tube 14. The wire 5 is also connected through a resistor 15 to a cathode heater 16 in the tube 14, and this heater is connected to a heater 17 in the oscillator tube by a wire 18, and from this tube to a heater 19 in one of the push-pull amplifier tubes by a wire 20, and then to a heater 21 in another push-pull amplifier tube, by a wire 22.

The heater 21 is connected to a heater 23 in the audio amplifier tube by a wire 24, and this is connected to a heater 25 in the detector tube by a wire 26, and from this to a heater 27 in the radio frequency amplifier tube by a wire 28, and the heater 27 is connected to the chassis by a wire 29 to the chassis at the point 30.

The cathode 33 of the tube 14 is connected to a wire 34 which conducts the rectified output of the tube 14 through a filter 35 to a positive B. supply wire 36 when A. C. current is used. A two point switch is provided, which has a contact 37 that may be moved to engage a contact 38 for unlimited power house D. C., B., when the device is on D. C. power, thereby cutting out tube 14.

Each of the cathode circuits of the tubes is connected to chassis through a condenser and a resistor, the connection of the cathode 39 having a condenser 40 therein with one terminal of the condenser connected to the cathode and the other to the negative B., and with the cathode also connected to one end of resistor 41 with the other end thereof connected to a variable resistor 42, the opposite end of which is connected to the grid 43 of the tube 44.

The variable arm 45 of the variable resistor 42 is connected to the wire 6 providing double volume control and cathode biasing for the control grids of the tubes. The cathode circuits of the tubes include condensers and resistors, and the numeral 46 indicates a condenser and resistor unit of the cathode 47 of the detector or amplifier tube, and 48 a similar unit of the cathode 49 of the audio amplifier tube. The cathodes 50 and 51 of the push-pull amplifier tubes are connected through a resistor 52 to the chassis through a common negative B., and the cathode 53 is directly connected to the chassis. The cathodes may also be provided with suppressors which may be connected to the cathodes at their sockets.

There are many circuits of various types and designs, however, in this the aerial 54 is the signal input and this is connected to a condenser 55 which is connected to a primary winding 56 of a

5 transformer, and from the primary winding to the chassis at the point 57, and the secondary winding 58, by inductance, takes the impulses to the intake control grid 59 of the radio frequency amplifier, the control grid being tuned by a condenser 60. One end of the winding 58 is connected to the stator of the condenser 60 and also to the grid 59, and the opposite end of the winding is connected to the rotary of said condenser and also to negative B. The primary winding 61 of another transformer is connected, at one end, to a plate 62 of the radio frequency amplifier tube, which is indicated by the numeral 63, and at the other to the positive B through the supply wire 36, and also to the screen grid 64, of the 15 tube, and this is also connected through a resistor 65 to the plus B through wire 36. The inductance winding 66 of the transformer takes the amplified sounds from the plate 62 to the input control grid 67 of the detector tube 68 which is 20 tuned by a condenser 69. One end of the winding 66 is connected to the stator of the condenser 69 and also to the grid 67, and the other to the rotary of the condenser and to negative B. The audio amplifier tube 44 is known as 25 30 resistance coupled.

The tube 68 is also provided with a resistor 70, one end of which is connected to the condenser 71, which is a .00025, and this end is also connected to a plate 72 in the tube 68, the other 35 end being connected to plus B through wire 36, and the other end of the condenser is connected to negative B. Another resistor 73 is provided with one end connected to plug B through wire 36, and the other to the screen grid 74 of the 40 tube 68, and also to the negative B through a condenser 73A are a 50,000 ohms resistor. The connection between the resistor 70 and plate 72 of the detector tube 68 is connected to a contact A of a three point switch 75, the arm of which 45 is connected to the control grid 43 of tube 44 and in this connection is a condenser 76, and it will be noted that with the arm 75 engaging the contact A the tube 44 will be working as a first audio amplifier.

50 In the push-pull amplifier tube circuit is a transformer, the primary winding 77 of which is connected to plus B at one end, through the transformer, which is of the push-pull type and indicated by the numeral 78, and then to a plate 55 79 in the audio amplifier tube 44 at the other, the plate 79 being the amplified output of the tube. A resistor 80 is provided, one end of which is connected to screen grid 81 in the tube 44 and the other to plus B. A similar grid 82 in one of 60 the push-pull amplifier tubes is also connected to plus B at this point. The winding 77 of the transformer supplies, by inductance the plate to grid coupling to the secondary winding 83 of the transformer 78 which supplies the sounds to control grids 84 and 85, the said grids being connected to each end of the winding 83 and the said winding 83 being tapped at the center and connected to negative B through a resistor 86. The plates 87 and 88 of the push-pull amplifier tubes 65 are connected to the central points forming the intermediate terminals of a double throw switch 89, and when the contact bars of the switch engage terminals 90 the said output passes through a push-pull primary winding of a transformer 75 92, one of said terminals being connected to one

end of the winding and the other to the other, and the winding is tapped at the center and connected to plus B. This primary winding 91 supplies the power audio output to the speaker winding 93 by inductance.

One of the novel features of the device is that by turning the switch 75 so that the arm will engage a contact B, a microphone may be plugged in at T and T₁, and the device is converted into a public address system to amplify sounds, voice, records, or telephones. The circuit is provided with a microphone transformer 94 one end of the secondary winding of which is attached to negative B and the other works through the condenser 76 to be amplified through the detector tube 44, and then through the power tubes 95 and 96 to the speaker 93. The primary winding 97 of the microphone transformer 94, is connected at one end to negative B and at the other to batteries 98 that supply the microphone. The arm 75 may be turned to engage the contact C thereby connecting to the terminal T₂, and this may be connected to the detector tube of any radio receiver for greater power output, and T₁ and T₂ may be attached to any phonograph attachment for a greater output.

Another novel feature is that by turning the arm of the switch 75 back to the contact B and the switch 89 to the terminals 99 the device will function as a transmitter working through the tube 44 and the power amplifier tubes 95 and 96 to the oscillator control grid 103 which is supplied through the condenser or crystal oscillator 108. The output of the tubes 95 and 96 is connected to one end of a coil 101 and the other end is connected to plus B through a resistor 102. The control grid 103 is also connected to one end of a coil 104 through a trimming condenser 105, and the plate 106 and screen grid 107 of the oscillator tube 108 are tied together at the socket and connected to the other end of the winding coil 104, which is tapped at the center and connected to plus B. The stator of condenser 108 is connected to the grid end to the winding 104 and another stator to the plate end of condenser 106, and the rotor is connected to chassis and plus B through another condenser 110 and cathodes 50 and 51. Another coil 111 takes the power output to an aerial 112 and the opposite end of the winding may be connected to the chassis as shown at 111A or left loose.

And another novel feature is that the transformer 78 controls the transmitted output in K. C., the K. C. being (on the spot) at what the transformer is built for or happens to be. The condensers 100, 109, and 105 are for neutralizing the oscillator grid 103 and the plate 106 and this tunes to frequency of the transformer 78. The control grid 103 is connected to negative B through a resistor 113, and the screen grid 115 of the tube 96 is connected to plus B.

In operation each element and unit, being connected to its proper potential, and with the plug 4 connected to a source of A. C. or D. C. current and with the switch 31 closed, current will flow through the wire 5, and through the system to the wire 6, passing through the heaters 27, 25, 23, 21, 19, 17, and 16, and through the resistor 15 to the line 5, the said heaters being in series with each other and with the resistor and lines.

In the design illustrated in Figure 2 the circuit of the power supply unit includes a full wave rectifier tube 116. The numeral 119 designates a transformer of the iron core type having

a primary winding 120 and a secondary winding 121 and the ends of the secondary winding are connected to the two elements 117 of the rectifier 116, and at the center of the winding 121 is a tap 122 which is connected to the chassis of a vacuum tube set with which the power unit is connected. The transformer 119 is provided with a winding 123, each end of which is connected to the heater 118, and this winding supplies filament or heater current for the rectifier.

A device for changing the circuit from A. C. to D. C. or from D. C. to A. C. is shown at 124, and this is formed with a core 125 in a coil 126 and as the coil is energized it will draw the armature 127 toward the solenoid formed thereby. One end of the coil is attached to the armature and the other through a wire 128, which has a chassis connection with a condenser 129 therein, and which is also provided with a power current switch 130, to a plug 131 which may be plugged into a current supply which may be either A. C. or D. C. The armature 127, when the coil 126 is not energized, engages a contact which is connected to the primary winding 120 of the transformer 119, and the other side of this winding is connected to the negative return wire 6 corresponding to a similar wire in Figure 1, and which is the negative intake for the filaments or heaters and is the plate supply for D. C. current. This wire is connected to the chassis at 129A and 129B makes chassis negative.

The numeral 132 designates a filtering choke and 133 the usual filtering condensers, and one end of the coil or winding of the choke 132 is connected to a filtered A. C.—D. C. plus plate supply wire 134 and this has a test outlet 135 therein. The other end of this winding is connected by a wire 136 to the heater element 118 of the tube 116, the rectified A. C. output. A wire 137 which is plus plate supply on D. C. is connected to the wire 136, and has a terminal 138 positioned for engagement by the armature 127 when the coil 126 is energized by D. C. current. When the armature is influenced by the solenoid it not only engages the terminal 138 but also engages the terminal 139 which is connected to the resistor 15 and also to a double pole single throw switch 140. On A. C. current a spring 141 holds the armature 127 in engagement with contact points 142, at which time the resistor 15 supplies the heater currents to the heaters 27, 25, 23, 21, and 19, as in Figure 1.

By contacting the terminals 99 with the switch 89 and closing the switch 140 a higher powered transmitter is provided. The power may be increased or decreased by using different types of tubes and may be controlled by the variable resistor arm 45. A resistor 143 in a connection from the switch 140 to a heater 144 supplies the heating current to the heaters 144 and 145 of the oscillating tubes 146 and 147, and a wire 142 supplies the plate current through the switch 140.

A push-pull interstage transformer 149 takes the amplified output of tubes 95 and 96 by wires 150 and 151 to each end of the primary winding 152, and this is tapped at the center and connected to plus B through test outlet 153.

The ends of the secondary winding 154 of the transformer 149 are connected to control grids 155 and 156 in the tubes 146 and 147, and this winding is tapped at the center and connected to negative B through a resistor 157. The cathodes 158 and 159 of these tubes are joined together and connected to negative B through a resistor

160, and the plates 161 and 162 are connected to the screen grids 163 and 164 at the sockets and the grids are connected to each end of the winding 165. The oscillator winding 165 is tapped at the center and connected thereby to a plus B current through a test outlet 166, and the plates 161 and 162 are connected together through a condenser 167, and in addition to this the plate 161 and the control grid 156 are connected together through a condenser 168, and the plate 162 and the control grid 155 are connected together through a condenser 169. The grids 155 and 156 are also connected together through a condenser 170 and to negative B, in the connection of which is a condenser 171 and cathodes 58 and 59. 15 These condensers 167, 168, 169, and 170 are neutralizing and tuning condensers, and the transformers 78 and 149 fix the K. C. in the output winding 172 and the condensers tune to that. That is type 6L6 tube and a 60 watt output is 20 good for type 100th tube also. With these parts a combination radio receiver, a power amplifier and a transmitter may be built on a 6" x 11" x 2" chassis. The other wires and units of the power circuit are the same as in Figure 1 and therefore the same reference numerals are used. The end 172A of the winding 172 may be connected to the chassis through a condenser as shown or may be left loose.

This type of power is illustrated as being in a combination circuit for receiving radio signals, power amplifying, transmitting and oscillating but it will be understood that it may be used in other types of circuits, and also that this type of combination circuit may be operated by transformer and batteries power parallel wired. In operation, with the plug 131 inserted in an outlet or connected to a source of current, and with the switch 130 closed, there is only one knob to 30 tune in by and control the input and output of the receiver, and the same knob operates the power amplifier and transmitter. It is therefore only necessary to make one move that cuts out the radio frequency and detector and turns on the power amplifier, and then move two knobs for transmitting, and then reverse the movement and it is a receiver again. With this device a radio can be operated as a receiver and transmitter of the same program.

The diagram shown in Figure 3 is similar to that shown in Figure 2, with parts omitted, the plug 173 being similar to the plug 4 and the current shifting device 174 being similar to the device 124, likewise in this design the cathodes of the tubes are individually connected to the chassis through resistor and condenser. A resistor 175, similar to the resistor 15 is in the circuit 176 to the heaters 177, and the cathodes 178 are connected to chassis through condensers 179 and resistors 180. A transformer 181, similar to the transformer 119, is also provided with the secondary winding also connected to the plates of the line rectifying tube 182. This circuit may be used independently or in combination with the parts shown in Figures 1 and 2 as may be desired.

It will be understood that other changes may be made without departing from the spirit of the invention. One of which changes may be in the use of any number of tubes in the set instead of the number shown, another may be in the use of other means for connecting the individual parts, another may be in the use of any other means for shifting from one current 75

to another, and still another may be in the use of filters or resistors of any other type, or in the use of other devices in the place of or in addition to any of the parts.

5 The construction will be readily understood from the foregoing description. In use the tubes, transformers, condensers, resistors, and other parts may be arranged in a relatively small compact casing and, as hereinbefore described, parts may readily be selected for receiving, other parts for amplifying, and other parts for transmitting. It will be understood, however, that this unit, or any parts thereof may be used for various types of radio apparatus, or for any purpose.

Having thus fully described the invention what I claim as new and desire to secure by Letters Patent, is:

1. A circuit arrangement of the class described, including a signal input circuit, an audio amplifying circuit including an audio amplifier vacuum tube, a push-pull audio amplifying circuit including audio amplifying tubes and a transformer, a loud speaker, means for controlling output of the first audio frequency amplifying tube whereby the output of the push-pull audio frequency amplifier may be controlled, an oscillator vacuum tube, an oscillatory circuit for said oscillator tube, and including a coil, an oscillatory circuit for the push-pull amplifying tubes and including a coil and the secondary of the push-pull amplifying transformer, an output circuit inductively coupled with the coils, a rectifier vacuum tube for supplying high tension current to the oscillator and amplifying vacuum tubes, and switch means operative in one position for connecting a loud speaker to the push-pull amplifying tubes and in another position for connecting the push-pull amplifying tubes in the oscillatory circuit for exciting the oscillator tubes and thereby controlling the output of said oscillator tubes.

2. A combination of elements as recited in claim 1, including a low resistance, a high milliampere speaker field connected in the rectified output, coils of said transformer being of the radio frequency and audio frequency type having the outside end of said secondary coil connected to the control grids and the intermediate terminal of the secondary to the chassis, and the primary outside end connected to the plate with the inside end to the positive terminal of said source of current.

3. The circuit arrangement as in claim 1, with a multi-point switch, including a movable contactor, normally set on one of its points for broadcast signal reception through said signal input and audio amplifying circuits to said loud speaker, a second transformer having its secondary connected between another of the switch points and said chassis and its primary between the latter and one of a group of pickup circuit terminals, an intermediate terminal of said group being connected to said chassis and a third terminal of said group to a companion point on said switch, the movable contactor of said switch being connected through a condenser to the grid of a detector-amplifier tube constituting a stage of said push-pull audio amplifying circuit, and a local power supply in circuit with said primary, 55 said group terminals being adapted for the interchangeable connection thereto of transmitter instrumentalities for the conversion of said circuit arrangement from use as an all wave band broadcast receiver to use as a transmitter of signals from said transmitter instrumentalities

through said push-pull audio amplifying circuit to said loud speaker.

4. The circuit arrangement as in claim 1, with a pickup circuit adapted to be connected to the grid of a detector-amplifier tube constituting a stage of said push-pull audio amplifying circuit, a multi-point switch in said pickup circuit normally set on one of its points for broadcast signal reception through said signal input circuit and said push-pull audio amplifying circuit to said loud speaker, said switch being adjustable to another of its points to establish connection

between said pickup circuit and said detector-amplifier tube, an all wave band broadcast signal output circuit, the first named switch means being operable to connect the output end of said push-pull audio amplifying circuit to said loud speaker when said signal input circuit is operative through said multi-point switch and also to connect said push-pull audio amplifying circuit to said broadcast signal output circuit when said pickup circuit is operative through said multi-point switch.

JAMES L. HOGAN.
